UNITED STATES PATENT OFFICE.

GAYLORD W. BEEBE, OF MINNEAPOLIS, MINNESOTA.

COMBINED PAPER-WEIGHT AND PENCIL-SHARPENER.

SPECIFICATION forming part of Letters Patent No. 597,870, dated January 11, 1898.

Application filed July 29, 1896. Serial No. 600,859. (No model.)

To all whom it may concern:

Be it known that I, GAYLORD W. BEEBE, of Minneapolis, Hennepin county, Minnesota, have invented a certain new and Improved 5 Combined Paper-Weight and Pencil-Sharpener, of which the following is a specification.

My invention relates to combined means for holding paper and sharpening pencils.

The invention relates particularly to a pencil-sharpener, the paper-weight being used as a convenient means of keeping the sharpener in sight on the desk and to bear various advertisements.

The object of the invention is to provide a 15 cheap and durable pencil-sharpener which will especially recommend itself by its simplicity and for the length of time during which the knife will remain sharp and ready for use.

20 The further object of the invention is to combine a pencil-sharpener with a paper-weight both for convenience and for advertising purposes.

The invention consists generally in a paper-weight or block having a hole into which the end of the pencil may be inserted and terminating in a cone or taper and said block having a surface cutting into the taper portion of the bore or hole and having a ledge 25 guide or shoulder, in combination with a long knife sharpened upon one edge and backing against said ledge, the edge of said knife extending over the opening into said bore, and means for binding the knife upon 30 said surface.

The invention further consists in particular details of construction and of combinations, all as hereinafter described, and particularly pointed out in the claims.

40 The invention will be more readily understood by reference to the accompanying drawings, forming a part of this specification, and in which—

Figure 1 is a perspective view of a combined pencil-sharpener and paper-weight embodying my invention. Fig. 2 is a vertical section on the plane indicated by the lines xx of Fig. 1. Fig. 3 is a transverse vertical section upon the plane indicated in the lines yy .

50 In the drawings the block or paper-weight portion of the device is preferably of an elongated form to permit the use of a long knife

or cutter-bar. The block is a light casting and on the under side is provided with the recess 2, the walls 3, 4, 5, 6, and 7 of which 55 are utilized for advertising, printed pasters being applied thereto. The greater part of the block comprises the raised flat portion 4, the top of which is parallel with the bottom of the block and is devoted to a more permanent and durable advertisement, desirable words, characters, or designs being etched or cast therein. About a third of the block in width is utilized for the pencil-sharpening device, which comprises a long blade 9, resting 60 upon the upper surface of the base and held in position by the clamping-screws 10. The edge of the block occupied by the pencil-sharpener attachment is cut away or depressed the entire length of the block, and 65 its surface has the recess 14, wedge-shaped in form, so that the blade 9 as it rests upon the surface of the block is inclined longitudinally and held at a uniform distance from the pencil-opening. In one end of the block, beneath 70 the blade 9, I provide the horizontal hole or opening 11, having a tapering inner end which comes to the surface of the recessed portion of the block at a point where the end of the pencil will be brought into contact with the 75 edge of the blade 9. The opening in the surface of the block leading to the hole 11 is the same length as the tapering portion. The knife 9 is made of thin bar-steel, and the inner edge thereof is finely sharpened. The 80 rear edge 12 is straight and butts or backs against the straight edge 13 of the recessed or depressed portion in the inclined surface. The screws 10 have wide bases or flanges which project out over the knife 9, and the 85 knife is of a greater thickness than the height of the slight shoulder or ledge 13, so that the bases of the screws will turn down firmly on the top of the knife to hold the same in position. The wedge-shaped recesses 14, before 90 spoken of, in the top of the inclined surface of the block, preferably project beneath the corner 17 of the block, so that when the knife is moved down the lower end will be concealed. By this means also it is possible to accommodate 95 the knife within a small space measured across the top of the block. When the part of the knife within the opening becomes dull, the screws are loosened and the knife is moved

down a short distance. An entire length of the knife may be thus used until the lower end of the knife approaches the end 18 of the block. The knife may be easily sharpened 5 upon an oil-stone, and as only one edge is sharp it may be grasped firmly in the hand when out of the paper-weight. The depression of the sharpener portion of the top of the block also carries the top of the screws into 10 the level of the surface 4, so that a number of weights may be piled one on the other as required in packing.

I prefer to make the base of sufficient length so that any portion of the knife-blade can be 15 adjusted opposite the hole and the whole cutting edge of the blade utilized without extending the knife beyond the end of the base, where it would be likely to cut the fingers of any one handling the device.

20 Having thus described my invention, I claim as new and desire to secure by Letters Patent—

1. In a device of the class described, the combination, with the base provided with a 25 depressed portion having an inclined upper

surface, the tapering pencil-hole leading to said inclined surface, of the knife-blade, the ledge forming a guide therefor, the binding screw or screws, and the flange provided on said screw or screws and extending over said 30 blade, for the purpose specified.

2. In a device of the class described, the combination with the base provided with a depressed portion having an inclined upper 35 surface, of the knife 9 arranged in a recess upon said inclined surface, the pencil-hole 11 provided in said base and coming to the surface in said recess, the ledge 13 provided on said depressed portion and forming a guide for the knife, and the binding screw or screws 40 10 provided in said ledge, and having flanges or bases extending over said knife, substantially as described.

In testimony whereof I have hereunto set my hand this 25th day of July, A. D. 1896.

GAYLORD W. BEEBE.

In presence of—

C. G. HAWLEY,

RICHARD PAUL.
